UNITED STATES PATENT OFFICE.

EDWARD T. SCHOONMAKER, OF NEW YORK, N. Y., ASSIGNOR TO THE ROGERS & HAMILTON COMPANY, OF WATERBURY, CONNECTICUT.

DESIGN FOR THE ORNAMENTATION OF SPOON-HANDLES.

SPECIFICATION forming part of Design No. 18,170, dated March 6, 1888.

Application filed January 31, 1888. Serial No. 262,589. Term of patent 7 years.

To all whom it may concern:

Be it known that I, EDWARD T. SCHOONMAKER, a citizen of the United States, residing at New York, in the county of New York and State of New York, have invented and produced a new and original Design for Spoon-Handles; and I do hereby declare the following to be a full, clear, and exact description of the invention, such as will enable others skilled in the art to which it appertains to make and use the same.

Reference is to be had to the accompanying drawing, which is an elevation of a spoon the handle whereof is designed in accordance with my invention.

The leading feature of my design consists in a lattice-work across the face of the shank or lower part of the spoon-handle, and a stalk extending from the base of the shank throughout the length of the handle, the upper portion of the stalk being foliated.

The essence of my design is the lattice-work across the shank, as specified, and I consider the foliate stalk as adjunctive.

a is the shank, *b* the lattice-work, *c* the stalk, 25 and *d* the foliage.

I claim—

The design for the ornamentation of spoon-handles and the like hereinafter shown and described, the same consisting in a representation of lattice-work across the face of the lower portion or shank of the handle, and a stalk extending from the base of the shank up throughout the length of the handle and foliated above the said lattice work, substantially as illustrated and described.

In testimony whereof I affix my signature in presence of two witnesses.

EDWARD T. SCHOONMAKER.
